CAN PUNCTURING AND POURING SPOUT

Frank H. Liljemark, Minneapolis, Minn., assignor to Plews Manufacturing Co., Minneapolis, Minn., a corporation of Minnesota

Filed Jan. 28, 1959, Ser. No. 789,655
1 Claim. (Cl. 222—89)

My invention relates to improvements in can puncturing and pouring spouts of the type utilized in gasoline filling stations for the dispensing of oils, anti-freeze liquids and the like.

When devices of the type above described are utilized in the dispensing of liquids from cans, there is a tendency toward leakage of some of the liquid to the outside of the pouring spout during the pouring or draining of the can. Also later when the can has been substantially emptied and has been set aside with spout still attached and now in an upright position, there is a further tendency for residual oil in the spout to find its way to the outside of the spout and flow onto the top and sides of the can causing loss of this otherwise salvageable oil, creating instead an untidy mess.

The primary object of my invention is the provision of an adequate yieldable sealing element encompassing the can puncturing blade immediately adjacent the inner end of the spout for efficiently receiving oil draining down the outside wall of the puncturing knife and directing same into the interior of the spout whereby to maintain the exterior of the spout in a relatively oil free condition at all times and simultaneously to effect a maximum salvage of oil or other fluid being drained from such used cans.

A further object of my invention is the provision of a device of the class immediately above described which is relatively inexpensive to produce, is extremely easy to install, which is rugged and durable, and is highly efficient in its operation.

The above and still further objects of my invention will become apparent from the following detailed specification, appended claim and attached drawings.

Referring to the drawings wherein like characters indicate like parts throughout the several views:

FIG. 1 is a view in side elevation of a can showing my novel device in operative position thereon, some parts being broken away;

FIG. 2 is an enlarged fragmentary view in vertical section, some parts being broken away;

FIG. 3 is a fragmentary sectional view corresponding generally to FIG. 1 but showing the structure thereof inverted for the purpose of draining the contents of a can into a storage receptacle;

FIG. 4 is a view in top plan of the sealing element of my novel device;

FIG. 5 is a bottom plan of the structure of FIG. 4;

FIG. 6 is a view in side elevation;

FIG. 7 is a view taken on the line 7—7 of FIG. 4;

FIG. 8 is a sectional view taken substantially on the line 8—8 of FIG. 4;

FIG. 9 is a fragmentary view in front elevation with some parts shown in section and some parts being broken away; and

FIG. 10 is a fragmentary view in side elevation taken generally on the line 10—10 of FIG. 9.

Referring with greater particularity to the drawings, the numeral 1 indicates in its entirety the handle and pouring spout of my novel invention. Preferably and as shown, the handle-spout 1 is longitudinally arcuate in shape and is formed from a pair of mating sheet metal sections sealed together along longitudinal seams 2 to provide an upper longitudinally generally convex section 3 and a lower generally longitudinally concave section 4.

2

The outer discharge end of the handle-spout 1 is identified by the numeral 5, whereas the somewhat enlarged inner end of the spout 1 is identified by the numeral 6. Preferably and as shown, the lower concave spout section 4 is formed to provide longitudinally spaced ribs 7 and the upper convex spout section 3 with longitudinally spaced recesses 8, which collectively facilitate grasping.

Adjacent the enlarged inner end 6 of the spout 1, the concave section 4 thereof is formed to provide an enlarged 10 longitudinally extended guide tongue 9, which as shown in FIGS. 1 and 2, is adapted to engage the outer cylindrical wall B of a can A, the flat top wall of the can A being identified by the letter C, whereas the upstanding bead thereof is identified by the letter D. A transversely 15 arcuate shoulder 10 is formed at the point of juncture of the spout section 3 with the guide tongue 9.

The convex upper spout section 3, adjacent the enlarged inner end 6 is formed to provide a relatively flat centering lip 11 which projects inwardly beyond the plane 20 of the shoulder 10 in generally opposed relationship thereto.

An elongated puncturing knife is identified in its entirety by the numeral 12 and comprises a longitudinally extended wall portion 13 in closely spaced relation to the 25 guide tongue 9 and laterally spaced blade-acting side flanges 14. As shown, the puncturing knife 12 is cross-sectionally U-shaped at its intermediate portion, the blade-acting side flanges 14 having a maximum depth adjacent the inner end 6 of the spout 1 wherein portions 15 engage 30 opposite sides of the centering lip 11. From the portions 15, the side flanges 14 taper toward the guide tongue 9 whereby to define blade-acting edges 16 and a puncturing point 17 in closely spaced relation to the free end 18 of the guide tongue 9. As shown particularly in FIGS. 35.2 and 3, the side flanges 14 of the puncturing knife 12 taper in the opposite direction from the centering portions 15 thereof whereby to define at the opposite end 19 a relatively flat anchoring tongue which projects into the enlarged inner end 6 of the spout 1 and is anchored 40 to the concave inner spout section 4 by means of an anchoring screw or the like 20.

Shown as being snugly received about the intermediate portion of the puncturing knife 12 is an elastic sealing element 21, preferably formed from suitable synthetic rubber so as to resist deterioration by lubricating oils, anti-freeze solutions, and the like. As shown, a radially 45 relatively thick and longitudinally deep portion 22 of the sealing element 21, having a generally U-shaped configuration, is interposed between the puncturing knife 12 and the guide tongue 9, at least circumferentially spaced portions thereof being in engagement with the shoulder 10, as indicated at 23, see particularly FIG. 9. Also preferably and as shown, the U-shaped portion 22 of the sealing element 21 is formed to provide longitudinally outwardly projecting fingers 24 at diametrically spaced points, one of each of said fingers projecting into the inner end of a recess 25 formed by the overlapping opposite longitudinal edges of the upper and lower spout sections 3, 4. In this manner, the opposite sides of the sealing element 21 are maintained in sealing engagement with the side flanges 14 of the puncturing knife 12.

At this point, it is important to point out that the upper convex spout section 3 adjacent the enlarged inner end 6 of the spout 1 defines inner end portions 26 immediately 55 adjacent said centering lip 11 and on opposite sides thereof which are generally normal to the centering lip 11 and one each of which overlies an opposite side flange 14 whereby to define abutments 27 which engage opposite side shoulder or seat portions 28 of mating contour therewith and formed in the sealing element 21. By this novel means, the sealing element 21 around the forward side portion thereof is adequately anchored against longitudi- 70

nal movement away from the puncturing point 17 of the puncturing knife 12, this in spite of the fact that the bar-like opposite inner side portion 29 of said sealing element 21 is unopposed by any projecting portion of the spout wall 6 during application of the puncturing knife 12 to a can top wall C merely snugly overlies the centering lip 11 so as to be free for relative movement as required after engagement with a can top wall C and still maintain sealing engagement between the knife 12, the can top wall C and the engaged portions of the spout 1.

As shown particularly in FIGS. 2, 3 and 5, the sealing element 21 is formed to define a continuous planar surface 30 adapted to be disposed in face to face relationship to the flat top C of a can A when the puncturing knife 12 has been caused to penetrate said top for the purpose of dispensing the primary contents from the can, or of subsequently draining from said can the film of oil or the like which tends to cling to the walls thereof during such dispensing operation. With the novel construction above described, it will be obvious that oil running down the outer surface 31 of the puncturing knife 12 will inevitably be engaged and intercepted by the circumferentially extended planar surface 30 of the sealing element 21. To assure a temporary retention of such oil, or other fluid, so as to guide same to the interior of the spout 1, I provide the sealing element 21 with an endless marginal flange 32 which, together with the planar surface 30 and the snugly encompassed sides of the puncturing knife 12 and the centering lip 11, forms a trough 33 which directs the flow of collected oil or the like through circumferentially spaced apertures 34 in said puncturing knife 12.

Preferably and as shown in FIGS. 2, 3, 5 and 7, the sealing element 21 is formed to provide an arcuate recess 35 for the reception of the bead D of the can A when the puncturing knife 12 is inserted into the can, as shown in FIGS. 1 and 2. The sole function of this recess 35 is to permit closer spacing of the planar surface 30 of the sealing element 21 with the flat top C of the can A adjacent the opening 36 therein. Obviously the flexibility of the trough-forming marginal flange 32 permits collapsing thereof during can puncturing movements without impairing the efficiency thereof as a trough-forming wall thereafter. For purposes of rigidity, the guide tongue 9 is formed with a longitudinally extended rib 37, and therefore the sealing element 21 is formed with a mating boss 38.

My invention has been thoroughly tested and found to be completely satisfactory for the accomplishment of the above objects and while I have shown a preferred embodiment thereof, I wish it to be understood that same

may be capable of modification without departure from the scope and spirit of the appended claim.

What I claim is:

In a device of the class described, an arcuate handle shaped spout the concave wall of which is formed at its inner end to provide an integral relatively wide longitudinally extended guide tongue adapted to engage the outer peripheral surface of a can, said tongue and spout at the point of juncture thereof defining a transversely arcuate shoulder, the convex wall of said spout projecting longitudinally inwardly beyond the plane of said shoulder and defining a relatively flat transversely extended centering lip, the longitudinally inner end portion of said convex wall on opposite sides of said centering lip defining arcuate abutments which extend between said centering lip and opposite ends of said arcuate shoulder, a cross sectionally arcuate puncturing knife having a longitudinally extended wall in closely spaced relation to said guide tongue and having blade acting side flanges which are in engagement with and which taper from opposite sides of said centering lip toward said guide tongue and define a puncturing point adjacent the free end of said guide tongue, portions of said blade acting side flanges underlying said arcuate abutments, an elastic sealing element snugly encompassing said knife adjacent the inner end of said spout and having longitudinally projecting anchoring fingers at diametrically spaced points thereon extending into sealing relationship with opposite inner end portions of said spout, and having opposite portions thereof in anchored mating engagement with said arcuate abutments for compression thereof between said blade acting flanges and said transversely arcuate shoulders around the forward side of said spout, the opposite inner side portion of said sealing element merely snugly engaging over the surface of said spout adjacent said centering lip, whereby said anchored forward portion of said sealing element is held against longitudinal movement relative to said knife and said opposite inner side portion of said element is free for such movement as is required when said knife is forced through a can top to maintain full sealing engagement therewith and with the centering lip of said spout.
